AUTOMATIC CODE SIGNALING DEVICE

Anthony Von Haase, Lakewood, Ohio, assignor to
Stewart-Warner Corporation

Application December 6, 1930, Serial No. 500,561

12 Claims. (Cl. 177—7)

The purpose of this invention is to provide an improved construction of a device operating automatically for giving an audible signal according to a predetermined code or formula, particularly adapted for controlling the sounding of a signal horn of a highway motor vehicle. It consists in the elements and features of construction shown and described as indicated in the claims.

In the drawings:

10 Figure 1 is a diagrammatic view for showing the location and arrangement of the vehicle dash of the different elements of the apparatus, viz, the horn, the controlling switches and the code-controlling mechanism with the energizing circuit 15 diagrammatically indicated.

Figure 2 is a wiring diagram of the entire system including the code control mechanism in detail.

Figure 3 is a plan view of the code controlling 20 mechanism.

Figure 4 is an elevation looking in the direction of the arrow 4 on Figure 3.

Figure 5 is an elevation looking in the direction of the arrow 5 on Figure 3.

25 Figure 6 is a detail portion of Figure 3 having parts omitted to clarify the showing of other parts.

Figure 7 is a detail elevation of an insulating mounting seen also in elevation in Figure 4 for parts of the electric circuit leading to and from the 30 different elements of the code control mechanism.

Figure 8 is a dissected section on an enlarged scale at the plane of the line 8—8 on Figure 7.

Figure 9 is a similar dissected section at the plane indicated by the line 9—9 on Figure 8.

35 Figure 10 is a similar dissected section at the line 10—10 on Figure 8.

Figure 11 is a plan view of the base which carries the code control mechanism with the latter shown in part in dotted line with diagrammatic 40 showing of the circuit connections.

Figure 12 is a perspective view of the pedal switch at open position for showing the contacts.

The construction shown in the drawings constituting this invention is arranged to operate an 45 automobile signal horn in a succession of soundings of varied individual duration and with varied intervals, in accordance with a predetermined signal code, the operation as to alternation of sounding and intervals and the duration of each sounding being automatically determined by a code control mechanism so as not to be dependent upon the expertness of the operator for conforming to the code.

50 This is accomplished by providing for cooperation with the horn-energizing circuit, operated by

a circuit in parallel with the horn-energizing circuit, a circuit interrupter for closing and opening a switch in the horn-energizing circuit at intervals, and for such closing and opening respectively, correspondingly to the durations of and 60 intervals between the code soundings, and the horn-energizing circuit is arranged to be controlled by circuit-controlling push button at the usual position on the steering column, as indicated in Figure 1, with the circuit wire running from 65 the source of current, as indicated at B in Figure 1, to the horn C, and from the horn to the control push button of the steering post switch, 111, and from the latter to ground, at 113 to 113^a and back to source B.

This, in respect to the horn-energizing circuit, it may be understood is the customary construction and installation for signal horns as now commonly constructed and connected for operation; and the present invention is designed to be utilized 70 in conjunction with this customary construction and installation without any change in the latter beside suitably connecting the circuit lines of the construction embodying the invention with the circuit of the customary horn installation.

The apparatus which is provided for association with the customary signal horn installation on a motor vehicle, comprises a circuit-interrupting, and thereby code-controlling, mechanism above referred to, which will now be described.

This mechanism is indicated in entirety at A, mounted on the instrument board, which will usually be the most convenient place for the apparatus. It embodies a small electric motor of 80 familiar construction indicated in entirety by the field and housing member, D, with the field poles shown at 21 and 22, the rotor armature with the windings indicated at 23, the commutator seen at 24, the commutator brushes at 25 and 26. 90 The armature rotor, 23, having its shaft, 23^a, journalled in the field housing, carries at its protruding end portion a worm, 27, cooperating with a mutilated gear member, 28, for operating a code controlling cam disk, 70, carried by the gear, 100 28, upon the under side of the latter.

The form of the code control cam, 70, may be noted at this point for understanding its operation as hereinafter described. It is a disk of insulating material and is rotated with the mutilated gear, 28, from a rest position at which its deepest notch or recess, 71, accommodates the free end of a spring conductor, 61, of the electric circuit in which the horn and motor are energized as hereinabove explained. Succeeding 105 110

this deepest cam recess in circumferential order are cam prominences, 72, 73, 74 and 75, alternating with recesses, 72^a, 73^a, 74^a and 75^a, the last merging in the deep recess, 71. The horn circuit is closed by the cam prominences encountering and deflecting the spring conductor and is opened by the reaction of the latter at the cam recesses.

The circumferential extent of the several cam prominences it may be understood would be made equal or varied according to the code length of the successive soundings of the horn, and similarly the recess in it would be made equal or varying according to the code length of the intervals between the soundings. The resulting character of the code signal may be readily understood upon observing the peripheral conformation of the cam disk, as seen in Figure 3.

At one end of the field housing outside the same there is mounted an electromagnet indicated by its winding seen at 40 extending from the current source as hereinafter described and whose exposed pole is indicated at 41 cooperating with an armature member, 42, which is carried by a latch device, 43, the latter being pivoted insulatedly on a post, 43^a, set in the base plate, H, and subject to the reaction of a spring, 43^b, coiled about the post and operating for holding the armature normally withdrawn from the magnet pole, 41, and for holding a contact, 43^c, carried by the latch intermediate its pivot and its terminal catch nose, 43^c, out of contact with a contact, 80^a, carried by a conductor, 80, mounted insulatedly in fixed position, as by an insulating disk, 81, carried at the outer end of the spool of the electromagnet, 40—41.

The gear, 28, carries on a stud axle, 31, on which the gear is journaled, a lever, 29, having at one end a gear segment, 29^a, whose radius is that of the unmutilated part of the gear, so that said segment may coincide with a corresponding segment of the gear and cooperate with the worm when the latter is standing at the mutilated segment of the gear.

45 The gear carries two stop pins, 33 and 34, between which the lever is free to oscillate over the gear face, the gear-segment-carrying arm stopping against the pin, 34, at one limit of the range of oscillation and the opposite arm stopping against the pin, 33, at the other limit, and the stop pin, 34, being positioned so that when the lever is stopped at that limit, the gear segment, 29^a, stands about midway in the mutilated arc of the gear.

55 At the normal position of the parts at rest, the lever, 29, is held nearly at the second mentioned limit of its range of oscillation by engagement of its end by the catch nose, 43^c, of the latch, 43, above mentioned, for which engagement the lever is furnished with a pin, 29^b; and it is thus held against the reaction of a flat spring, 36, attached at one end to the gear-segment-carrying arm of the lever, 29, as seen at 29^c, and stopped at the other end against the stop pin, 33, being intermediately flexed over a collar, 31^a, on the stud axle, said collar serving also to retain the lever closely, but free for the oscillation described.

70 At its normally latched position, the gear-segment-carrying end of the lever stands slightly withdrawn from a position for engagement with the worm, 29, of the motor shaft, which at said position of the parts stands at the mutilated portion of the gear, having in the last preced-

ing operation of the horn driven the gear out of mesh with the worm.

Upon disengagement of the latch from the free end of the lever, 29, by means hereinafter described, the reaction of the spring, 36, swings the gear segment end of the lever into encounter with the worm, 27, and at the same time nearly into engagement with the stop pin, 34, on the gear.

Upon the release of the lever 29 from the latch, the movement of the lever due to the reaction of the spring, 36, as described, carries the end of the lever having the pin, 29^b, and said pin, clear of the latch, and the operator having released the push button 111, causing the magnet to be de-energized and to cease attracting the armature, the reaction of the spring, 43^b, immediately swings the lever inward, bringing the contacts, 43^d and 80^a, on the latch, 43 and conductor, 80, respectively, into cooperation for grounding the motor-energizing circuit, causing the motor to start.

At the rest position of the gear before the lever is released from the latch, the code controlling cam, 70, hereinafter described in detail, which is fixed to the gear, 28, at the under side of the latter, stands with its deepest notch, 71, registered with the free end of a conductor, 61, hereinafter described as to its function in the motor energizing circuit; and when the motor starts 105 and rotates the gear, 28, and the cam, 70, the cam actuates the free end of said conductor, 61, to the limit of the cam protrusion next following said deepest notch, 71, thereby effecting a closure of the circuit between the conductor, 61, and the adjacent element of the circuit, as herein-after explained.

The circuit-controlling connections for energizing the motor for controlling the horn-energizing circuit to determine the soundings in accordance with the predetermined code will now be described.

From the current source indicated conventionally at B, circuit wire, 100, leads to an insulated binding post, 101, at any convenient part of the vehicle, from which point circuit wires in parallel, 102 and 103 lead respectively to the code control mechanism, A, as mentioned above, and to a binding post, 104, on the horn, C, the connection of the wire, 102, with the code control mechanism being indicated at 105 in diagram Figures 3 and 4, and the remainder of the circuit from that point is hereinafter fully described.

From a second binding post, 104^a, on the horn, circuit wire, 106, leads to a switch device preferably mounted for operation by a pedal switch indicated by its push button at 107, and from this switch, circuit wires in parallel, 108 and 109, lead respectively to the code control mechanism, with connections indicated at 110 on Figure 3, and to 130 a switch indicated by its push button, 111, on the steering column or other place on the vehicle convenient for manual operation. From this push button, 111, circuit wire, 112, leads to ground indicated at 113 in the diagrammatic view Figure 1. 140

It will be noted by reference to Figure 2 that the line, 106, from the horn to the pedal switch is parted into two circuit members in parallel 106^a and 106^b, of which the line, 106^a, leads to the contact, 107^a, of the switch of which the line, 106^b, leads to the contact, 107^b, of the switch, 107, and from which contact the line, 109, leads to a switch, 111, which in effect makes this branch bypass the pedal switch, 107, and constitute circuit 150

line direct from the horn to the switch, 111, from which the circuit runs direct to the ground.

This it will be recognized amounts to running two lines from the horn binding post, 104^a, one to the switch, 107, and the other direct to the switch, 111, the latter making the horn operable in the customary manner through the switch, 111, alone, as hereinbefore described.

The circuit served by the circuit wires, 102 and 108, hereinbefore mentioned as in parallel with the lines, 103 and 109, respectively, with their connections at 105 and 110, respectively, are continued through connectors and contacts and binding screws mounted in an assemblage of insulating blocks indicated in entirety at E, and which with said conductors and binding screws may be understood by reference to the dissected sectional views Figures 6, 7 and 8, by reference to which the same will now be described.

20 The insulating blocks, 50, 51, 52 and 53 are mounted by clamp screws, 54 and 55, on the motor field and housing, D, which, being mounted on the base plate, H, is adapted to constitute a ground connection. A conductor, 60, clamped 25 between the insulation blocks, 51, and 52, laps the conductor, 61, also clamped between said blocks and which is operatively connected by a binding screw, 63, mounted in the upper end portion of the block, 52, with the circuit wire, 108, 30 above mentioned, which is held to said binding screw between nuts, 64 and 64^a.

The conductor, 61, which is flexibly resilient protrudes from the insulating mounting and carries a contact, 61^a, which is arranged to be normally in contact with a contact member, 62^a, 35 carried by the conductor, 62, which latter is clamped between the insulating blocks, 52 and 53, between which, lapping the conductor, 62, there is clamped a conductive terminal, 65^a, of a 40 circuit wire, 65, which leads from the winding, 40, of the magnet, 41.

Between the blocks, 51 and 50, there is clamped a conductor, 66, which projects parallel to the conductor, 61, and carries a contact, 66^a, positioned for cooperating for circuit connection with the contact, 61^a, of the conductor, 61, upon the latter being sufficiently flexed toward the conductor, 66. Between the blocks, 51 and 50, there is also clamped in contact with the conductor, 66, a 50 conductor, 67, which is folded around the end of the block, 50, and clamped between said block and motor housing, D, and thereby adapted to effect ground connection completing the circuit for energizing the horn.

55 A conductive terminal, 102^a, of the circuit wire, 102, hereinbefore mentioned, is clamped between nuts, 74 and 74^a, to a binding screw, 73, mounted by means of the nut, 74, in the upper part of the insulating block, 52, and a circuit wire, 73^a, engaged under the head of the binding screw, 73, leads to the motor field winding and commutator brushes with a branch-in-parallel, 73^y, leading to the winding, 40, of the electromagnet, 41, from which winding, as above noted and indicated at 65 in the wiring diagram Figure 2, a circuit wire leads back to the insulating assemblage where it makes connection with the conductor, 62, containing the motor field winding whose circuit is completed by a wire, 76, and 76^a, to and from the 70 commutator brushes, 26, to the insulated conductor, 80, as above described.

Summarizing the foregoing description of circuits:

The circuit in which the motor is energized 75 when both the pedal switch button and the steer-

ing post switch button are operated, may be traced in the wiring diagram Figure 2 with the assistance of other figures as follows:

From the current source, B, to binding post, 101; thence by wire, 102, to binding screw, 73, on the member, 52, of the mounting assembly (see Figure 10); thence by branch-in-parallel at 73^x to the field winding of the motor, and thence as indicated at 76 to the commutator brushes, and thence by line, 76^a, to the insulated contact carrier, 80, and contact, 80^a; thence by way of the contact, 43^d, and pivoted conductor, 43, to ground as indicated at 43^x, when the contacts, 43^d and 80^a, are brought together; which is effected as above described upon release of the steering post switch button de-energizing the magnet, 41, which, until said release, has been energized in the circuit which may be traced from the branch-in-parallel, 73^y, by way of the magnet winding, 40; line, 65; conductor, 62; contact, 62^a; contact, 61^a; conductor, 61; conductor, 60, binding screw, 63; line, 108; pedal switch, 107; and steering column switch, 111, to ground at 113. Meanwhile it will be noted that the circuit branch, 73^y, in parallel with the line, 73^x, through the motor, having the duty only of energizing the magnet pole, 41, affords easier path for the current than is afforded by the motor energizing circuit; and the current will therefore by-pass the motor when this branch-in-parallel is closed for permitting current flow through it. And thus the magnet being energized without the motor being started operates by attracting the armature, 42, to separate the contacts, 43^d and 80^a, opening the branch circuit through the motor winding.

Upon considering these branch circuits-in-parallel it will be noted that due to the spring, 43^b, the circuit through the motor windings is normally closed at the contacts 43^d and 80^a, so that upon the operation of the two push buttons, 115 the circuit will be closed simultaneously through both branches, 73^y and 73^x, to the magnet winding, 40, and the motor winding, 23. The branch-in-parallel, 73^y, leads by line, 65, to a conductor and contact carrier, 62, contact, 62^a, contact, 61^a, 120 and conductor and contact carrier, 61, to the binding screw, 63, and thence to the pedal switch, 107, and thence to the steering wheel column push button, 111, and to ground at 113; this is the course of the current when the latch lever, 43, is 125 engaged at the catch nose, 43^c, by the pin, 29^d, of the lever arm, 29, as seen in Figure 3, and indicated in a wiring diagram Figure 2; and the motor is de-energized by the current by-passing it as above described.

But while the push button, 111, is held closed, since the current through the horn finds direct course to the ground by wires, 109—112, no effective current will pass by way of the wire, 108, to the motor energizing circuit, this de-energizing 135 of the motor being independent of the de-energizing by by-passing through the magnet winding, 40, as above described, and the motor is thus caused to stop when the push button, 111, is operated, regardless of the operation of the magnet 140 for actuating the part, 43, and opening the circuit at 80^a and 43^b.

Upon considering the circuit connection and course as above described, it may be seen that when the operator simultaneously operates the 145 pedal switch button and the steering column push button, closing the circuit at both points, a circuit is established from the battery by the wire, 103, to the horn and thence by the wire, 106, to the pedal switch, 107, and thence by the wire, 150

109, to the steering column push button, 111, and thence by the wire, 112, to ground at 113, which causes the horn to be sounded. And simultaneously a circuit is established by the wire, 102, the 5 binding screw, 73, and thence by the wire, 73^x, and branch-in-parallel 73^y to the electromagnet winding, 40, and thence by the return wire, 65, to the conductor, 62, and through the contacts, 62^a and 61^a, of the conductors, 62 and 61, respectively, to 10 the conductor, 61, and thence by binding screw, 63, and circuit wire, 108, to the pedal switch button, 107, thence to push button, 111, and thence to ground closing the circuit by which the magnet, 40, 41, is energized for operating the latch, 43, to 15 release the gear segment lever, 29, and cause the gear segment due to the reaction of the flat spring, 36, to encounter the worm for making operative connection of the motor mechanism with the gear, 28, while simultaneously the latch, 43, released from the duty of locking the lever, 29, is 20 operated by the spring, 43^b, for closing the motor-energizing circuit through the contacts, 43^d and 80^a.

And it will be seen that the motor-energizing 25 circuit connections will continue thus closed for operating the interrupter so long as the pedal switch, 107, is held closed. But while the push button, 111, is held closed, since the current from the horn finds direct course to ground by the 30 wires, 109 and 112, no effected current will in any event pass by the wire, 108, to the motor energizing circuit, this avoidance of energizing the motor being independent of the avoidance due to the energizing of the magnet for opening the motor-energizing circuit at the contacts, 43^d and 80^a, causing the motor to be stopped. And accordingly it will be noted that regardless of the 35 specific arrangement of the circuit connections for opening and closing the circuit at 43^d and 80^a, the motor will be stopped and the horn continuously sounded whenever the push button, 111, is operated.

Accordingly by holding the button, 111, closed, the operator may prolong the first sounding of 45 the horn to any length; and upon releasing the button, 111, continuing to hold the pedal switch, 107, closed, the sounding of the signal would be continued accordingly.

Also, as above described, the horn will be sounded in the customary manner as if no code mechanism were present, if the push button only is 50 operated.

It is considered desirable, for the same reason that the code signal is considered preferable to 55 the customary abrupt and more or less alarming and irritating signal, that when the customary signal is resorted to, it should be softened in comparison in the individual soundings of the code signal. And for that purpose there may be interposed in the course of the wire, 106, for making 60 a circuit connection in parallel with the switch, 111, and the wire, 108, leading to the switch, 107, a high resistance element indicated at 106^x, in the wiring diagram, Figure 2, leading to the contact, 107^a, of the switch, 107, from which the wire, 109, leads to a switch, 111, thus enabling the current to by-pass the switch, 107, or the connection therefrom by the wire, 108, to the interrupter conductor, 61. This expedient it will be seen limits the current which energizes the horn in accordance with the resistance of the wire, 106^x, when by reason of the switch, 107, being opened, the current cannot make its return course from the horn by way of the contact, 107^b, from the 75 wire, 106.

I claim:

1. A mechanism comprising a rotatably driven element of a gear train; a cooperating element of such train arranged to be out of operative connection with the first mentioned train element 80 at a rest position of the mechanism; a third train element mounted on the second mentioned train element for movement relatively thereto and to the first mentioned train element to effect driving engagement of the first with the second; spring means reacting on said third gear element for its said movement for said train engagement; means locking it against the reaction of said spring out of said train-engaging position, and an electromagnet and a circuit in which it is energized and a magnetic element carried by said locking means in position to be 85 attracted by the electromagnet for disengaging the locking means to permit the movement of the train-engaging member into train-engaging 90 position. 95

2. In an apparatus for the purpose indicated, an electrically energized signaling device; a main circuit in which it is energized comprising a current source, electrically conductive parts of 100 the signaling device, a normally open switch including a main and an auxiliary movable contact-carrying element and conductive connection from said switch back to the current source; a circuit-interrupting mechanism comprising a 105 rotatable cam device having alternate protrusions and recesses constituting a cycle arranged for cooperating with the movable element of the main circuit switch for alternately closing and opening said circuit and alternately energizing 110 and de-energizing the signaling device in accordance with a code predetermined by the cycle of alternating cam protrusions and recesses, and a gear train by which the cam device is rotated through the cycle; a motor by which the gear train is driven; an electric circuit in which the motor is energized comprising the current source, the motor windings, a motor controlling switch including a main and a cooperating contact carrier and contacts carried thereby, and conductive 115 connection from said switch back to the current source, said gear train comprising a continuously rotated element, and a cooperating gear element arranged to be out of operating connection with the continuously rotating element at the normal 120 inoperative rest position of the cam and gear train; a third gear element mounted on the second mentioned gear element for movement relatively thereto and to the continuously rotating train element to effect driving engagement of 125 said first and second train elements; spring means for reacting on the third gear element for its said movement for train engagement; means locking said third gear element against the reaction of said spring out of said train-engaging 130 position; an electromagnet, a branch of the motor circuit in which said magnet is energized, said branch comprising the winding of said electromagnet and conductive connections thence to the current source including personally operable 135 switch means interposed in said conductive connections, whereby the energizing of the electromagnet is dependent upon operation of said personally operable switch means for closing said branch circuit, said electromagnet having an armature carried by said locking means positioned relatively to said electromagnet for attraction by the magnet when the latter is energized; whereby the magnet operates the locking 140 means for releasing the gear element. 145

3. In the construction defined in claim 2, the 150

- gear train comprising a mutilated driven gear associated with the cam element for rotating the latter through its cycle, and a driving element arranged to be registered with the mutilation of the driven gear at the normal inoperative rest position of the gear system, the cam device carried by the mutilated gear having means for interrupting the motor-energizing circuit at the cycle-ending position of the cam, said position corresponding to the position of registration of the gear mutilation with the driving element.
4. In the construction defined in claim 2, the continuously rotated element of the gear train consisting of a worm carried by a shaft of the motor, and the cooperating gear element being a mutilated gear and carrying the cam, the third gear element consisting of a lever having a gear segment terminal and pivoted centrally with respect to said segment terminal and with respect to the mutilated gear and carried by the latter, and having limited range of oscillation relatively to the gear between stops carried by the gear for so limiting it, the gear feature of said third gear element being a gear segment having radius equal to that of the unmutilated part of the mutilated gear, the spring means mentioned being arranged reacting between the lever and the mutilated gear tending to hold the lever stopped at one limit of its oscillation, the opposite end of the lever from the gear segment constituting the means of engagement of the catch, and the spring serving for stressing the gear segment into encounter with the worm to effect rotative movement of the gear and thereby of the cam when the motor starts.
5. In an electrically operable apparatus having a main energizing circuit and requiring for its purpose intermittent operation, means for such intermittent operation comprising a movable circuit member in the main circuit, a rotatable cam operatively associated with said movable circuit member for alternate opening and closing of the circuit as the cam member is rotated through its cycle, a gear train having intermeshing gear elements by one of which the cam element is carried for rotation through its cycle, an electrically energized motor by which the gear train is driven, said gear train comprising a primary gear element driven continuously by the motor, a partly mutilated gear which carries the rotatable cam dimensioned and positioned for meshing as to its unmutilated part with said continuously driven gear element, and a third gear element carried by said mutilated gear in the rotation of the latter and movable radially thereof for meshing and withdrawing from meshing with said continuously driven gear element at the position at which the mutilation of the mutilated gear registers with said continuously driven gear element, and means cooperating with the mutilated gear in its rotation carrying said third element for withdrawing the latter from meshing position at a predetermined stage in the rotation of the cam by said mutilated gear.
6. A mechanism comprising a rotatably driven element of a gear train; a cooperating element of said train arranged to be out of operative connection with the first mentioned train element at a rest position of the mechanism; a third train element mounted on the second mentioned train element for movement relatively thereto and to the first mentioned train element to effect driving engagement of the first train element with the second; spring means reacting on said third element for its movement for said train engagement; means locking it, against the reaction of said spring, out of said train-engaging position, an electromagnet and a circuit in which it is energized, and a magnetic element carried by said locking means in position to be actuated by the electromagnet for disengaging the locking means to permit movement of the train-engaging member into train-engaging position, the initial element of the gear train being a motor-driven worm, the rotated element being a mutilated gear meshing with said worm, and the third element being a gear segment terminating a lever, said lever pivoted centrally with respect to the mutilated gear; a stop on the gear for limiting the rotative movement of the lever with respect to the gear and engaging the lever for carrying it with the gear in the rotation of the latter, the spring means reacting between the lever-engaging means and the gear holding the lever normally in encounter with said stop during the rotative movement of the gear for carrying the lever to locked position, said stop being positioned relatively to the mutilated segment of the gear for being withdrawn from the lever at the locked position of the latter in the continued rotation of the gear to position of interruption of its rotation due to the mutilated segment becoming registered with the worm.
7. An apparatus comprising an electrically operated device, two circuits in which it is energized, separate personally operable switches interposed in said circuits respectively, said circuits having a part-in-common, intermediate said two switches, said device being operatively connected in said part-in-common; comprising operating connections extending for personal operation and automatically operating means for controlling one of said circuits for energizing said device interrupted, the resistance of said last mentioned circuit being so substantially greater than that of the other circuit that when the personally operable switch is operated for closing said other circuit, negligible current passes by the circuit having the automatic interrupted operating circuit controlling means.
8. In an apparatus for the purpose indicated, a main circuit comprising a current source, an electrically energized signaling device, a normally open switch including a main and an auxiliary contact-carrying element and conductive connections from the main contact carrier to the current source; automatically operating means for opening and closing said normally open switch, said operating means comprising a rotatable cam and an electric motor for rotating the cam; a spring-stressed catch for locking the cam at open position of said main circuit switch; an electromagnet; a normally closed back contact on said normally open switch; a circuit from the current source through the electromagnet and to the back contact; an armature for the electromagnet; a motor-energizing circuit separate from the main circuit leading from the current source to the motor winding and thence to and comprising a normally open switch, and from said switch back to the current source; means connecting said catch and the movable element of said last mentioned motor circuit switch to said armature, so that the catch is released when the armature is attracted by the magnet, and the motor switch is closed when the armature is released by the magnet; and a normally open personally operable switch interposed in the main circuit between the signaling device and said first

mentioned normally open automatically operated switch device.

9. In the construction defined in claim 8, a branch from the main circuit between the signaling device and the personally operable switch, said branch leading back to the current source, and a second normally open personally operable switch interposed in said branch; whereby upon closing said interposed switch the current is 10 short-circuited past the first mentioned personally operable switch and the signaling device is energized without control by the rotatable cam.

10. The construction defined in claim 8, the spring-stressed catch member being pivotally 15 mounted and carrying rigidly the electromagnet armature member and the movable element of the motor circuit switch in angular relation to each other and to the operating arm of the catch member for causing the cam-locking movement of the catch member to be the released movement of the armature, and the circuit-closing movement of the motor circuit switch.

11. In the construction defined in claim 8, a motor-driven gear train member by which the 20 rotatable cam member is actuated; a primary motor-driven gear train element arranged to be out of operative connection with said cam-member-actuating train element at rest position of the mechanism; a third train element mounted 30 on said cam-member-actuating train element for movement relatively thereto and to said primary motor-driven train element, to effect driving engagement of said primary train element with the cam-actuating train element; spring means reacting on said third train element for train-engaging movement of the latter, said third train element serving for the engagement of the spring-stressed catch member for locking the cam member as defined in claim 8.

40 12. The construction defined in claim 8, the

rotatable cam having alternating protrusions and recesses for alternately closing and opening the switch to operate the signal in cycle according to a code; a motor-driven gear train comprising a mutilated gear by which the cam element is 80 actuated for rotation through the cycle, said gear train comprising a gear element connected with the motor for continuous rotation while the motor is operating and arranged to be registered with the mutilation of the cam-actuating gear at a normally idle or rest position of the gear train, the gear train comprising a third gear element mounted on the mutilated gear and spring-stressed for movement relatively thereto for engaging the continuously rotated train element at 85 the position of the mutilated gear at which its mutilation is registered with said continuously rotated train element, the cam having its protrusions and recesses arranged for operating the motor circuit switch for interrupting the energizing of the signaling device at said position of registration of the gear mutilation with said continuously rotated gear element, said third gear train element being extended in position for constituting the engagement of the spring-stressed 90 cam-locking catch mentioned in claim 8, and being pivotally mounted on the cam-actuating gear for being held by the catch out of engagement with the continuously rotated train element, whereby the disengagement of the 95 spring-stressed catch unlocking the rotatable cam releases the third train member for engagement with the continuously driven train element for rotating the cam, and the engagement of the third train element by the spring-stressed catch, 100 locking the cam, disengages said third train element from the continuously driven train element for arresting the rotation of the cam.
